UNITED STATES PATENT OFFICE.

OTTO C. ECKERT AND LOUIS COHEN, OF PROVIDENCE, RHODE ISLAND.

DESIGN FOR A PENHOLDER-HANDLE.

SPECIFICATION forming part of Design No. 22,524, dated June 13, 1893.

Application filed April 17, 1893. Serial No. 470,768. Term of patent 3½ years.

To all whom it may concern:

Be it known that we, OTTO C. ECKERT and LOUIS COHEN, both of Providence, in the county of Providence, and State of Rhode Island, ⁵ have invented and produced a new and original Design for Penholder-Handles, of which the following is a specification, reference being had to the accompanying drawings, forming part therewith.

Figure 1 represents a view of a penholder-handle illustrating our new design. Figs. 2 and 3 represent cross-sectional views of the same to more clearly illustrate our design.

The leading features of our new design for penholder-handles consist of the main outlines of the handle and the spirals ornamenting the surface, the spirals having a circular cross-sectional shape.

Number 5 in the drawings indicates the

base of the penholder-handle which gradually ²⁰ tapers from the base toward the top. In this tapering surface are the spiral grooves 6—6, and following the central lines of the grooves are the spiral ribs 7—7 of a color contrasting to that of the penholder-handle and of a circular cross-sectional shape; the top of the handle is ornamented with the cap 9 also of a different color from that of the handle.

What we claim is—

The design for a penholder-handle as herein ³⁰ shown and described.

In witness whereof we have hereunto set our hands.

OTTO C. ECKERT.
LOUIS COHEN.
